ABSTRACT: A gas burner has a venturi portion, a crossover portion downstream of the venturi portion and a head portion downstream of the crossover portion. The head portion includes an elongated inclined port from which a gas and air mixture issues for combustion adjacent thereto. The port has a lower region of enlarged width and an upper region of reduced width, each region being defined by a pair of spaced parallel edges. The region of reduced width has its upper termination adjacent the crossover portion whereby ignition of the gas and air mixture issuing from the port may be effected from a flame present at the crossover portion. The region of reduced width minimizes burn back.

GAS BURNER

BACKGROUND OF THE INVENTION

This invention relates to an improved gas burner particularly adapted for use in a home-heating furnace.

In the manufacture of home-heating furnaces, it is desirable to be able to standardize parts of the burner assembly so that assemblies of different B.t.u. outputs may be assembled by installing different quantities of a standardized gas burner. These individual burners are assembled into a heat exchanger in a side-by-side relationship, the number depending upon the desired capacity of the furnace. Since it is desirable to provide only a single pilot light to ignite all the burners simultaneously, crossover means are provided to transport the pilot flame to the adjacent burner and from that burner to the next, etc. It is desirable also to locate the crossover means such that it does not interfere with normal combustion after ignition has been effected. When gas burners having a single combustion port are used it is possible, for example, to employ a flame deflector, i.e., a means to deflect the flame issuing from the combustion port of one burner to the adjacent burner to effect crossover ignition, but the deflector remains positioned in the path of the main flame after ignition. This may be undesirable.

It is an object of the present invention to provide an improved gas burner particularly adapted for use in a home-heating furnace.

It is another object of this invention to provide a single combustion port gas burner having an improved ignition crossover means.

SUMMARY OF THE INVENTION

Briefly stated, in accordance with one aspect thereof, the present invention relates to a gas burner having a hollow body adapted to receive a combustible gas and air mixture at the upstream end thereof and flow therethrough to issue at the downstream end thereof. The body includes a head portion having spaced walls defining a port from which the gas and air mixture issues for combustion adjacent the port. The spaced walls have a first pair of spaced edges defining a region of the port having an enlarged width and a second pair of spaced edges defining a region of the port having a reduced width. A crossover portion is provided upstream of the head portion but adjacent the region of reduced width whereby ignition of the gas and mixture issuing from the port may be effected from a flame present at the crossover portion.

BRIEF DESCRIPTION OF THE DRAWING

While the specification concludes with claims particularly pointing out and distinctly claiming the subject matter which is regarded as the invention, it is believed the invention will be better understood from the description of the preferred embodiment taken in connection with the accompanying drawing, in which:

FIG. 1 is a perspective view of the gas burner of the present invention;

FIG. 2 is a top plan view of the burner of FIG 1;

FIG. 3 is a side elevation view of the burner of FIG. 1; and,

FIG. 4 is an end view of the burner of FIG. 1 looking toward the head portion thereof.

DESCRIPTION OF THE PREFERRED EMBODIMENT

Referring now to the drawing, there is illustrated a cast iron gas burner 10 having a venturi portion 11, a crossover portion 12 and a head portion 13 integrally forming a hollow body 14. The upstream end 15 of body 14 is adapted to receive a combustible gas and air mixture which flows through hollow body 14 to issue at the downstream end 16.

Gas is admitted to burner 10 from an orifice 17 in a pipe 17a and air is admitted through openings 18. The gas and air mixture is thoroughly mixed as it passes through venturi portion 11. After leaving venturi portion 11, the major portion of the combustible gas and air mixture issues from burner 10

through port 19 in head portion 13. A small portion of the combustible gas and air mixture issues from elongated slots 20 in crossover portion 12.

As discussed above, in a home-heating furnace the general practice is to provide several burners, such as burner 10, in a side-by-side fashion, the exact number depending upon the desired capacity of the furnace. A conventional pilot light (not shown) is provided adjacent the crossover portion 12 of one of the burners 10. With the side-by-side relationship of the burners, the individual crossover portions, each of which comprise a boss projecting laterally from body 14, are contiguous or closely spaced from each other so that, as gas is admitted from the individual pipes 17, the small portion of the gas and air mixture which issues from slots 20 of burner 10 closest to the pilot light will ignite. Because of the contiguous or closely spaced relationship of crossover portions 12, the flame will be transported from the pilot light to all of the burners by means of the flame moving from crossover portion 20 to crossover portion. It is, of course, necessary to transport the flame from the slots 20 of the crossover portions 12 to the ports 19 in order to effect ignition of the main portion of the gas and air mixture. The present invention provides an improved means for effecting transport of the flame from the crossover portion 12 to the port 19.

Port 19, at its lower portion, has a region 21 of enlarged width defined by substantially parallel edges 22, and at its upper portion it has a region 23 of reduced width defined by substantially parallel edges 24. Edges 22 and 24 comprise the upper internal extremities of walls 25 of head portion 13. Walls 25 are spaced from each other to form a hollow passageway therebetween which communicates with venturi portion 11. Region 23 of port 19 extends upwardly and rearwardly and terminates adjacent one of the slots 20. The adjacency of region 23 to slot 20 is such so as to allow the flame to be transported from slot 20 to region 23 and thus ignite the gas and air mixture issuing from port 19. By locating crossover portion 12 entirely upstream of head portion 13, and, more specifically, port 19, the crossover portion in no way interferes with normal combustion taking place at port 19. However, it is necessary to extend port 19 up through its region 23 of reduced width so that port 19 and slot 20 are closely spaced to allow transport of the flame from slot 20 to port 19.

With a gas burner having a single combustion port, such as port 19 of burner 10, it is generally desirable to incline the port to project the combustion flame upwardly and outwardly. Port 19 is so inclined by inclining the edges 22 and 24 defining port 19 upwardly and rearwardly toward the upstream end of the body 14. The velocity of the gas and air mixture in the upper portion of the inclined slot 19 is relatively low and because of this there is a tendency for the gas and air mixture to burn back into venturi portion 11 of burner 10. By providing the region 23 of reduced width, the tendency for the gas and air mixture to burn back into venturi portion 11 is minimized due to the difficulty of the flame to burn back through a narrow opening. With gas pressures normally encountered in domestic-heating furnaces a width of approximately 0.15 to 0.25 inch for region 21 and a width of approximately 0.12 inch for region 23 works well when crossover slot 20 has a width of approximately 0.04 inch.

It should now be evident that the present invention provides an improved gas burner particularly adapted for use in a home-heating furnace having an improved crossover means which in no way interferes with normal combustion at the main burner port.

It should be apparent to those skilled in the art that while there has been described what, at present, is considered to be the preferred embodiment of this invention in accordance with the Patent Statutes, changes may be made in the disclosed apparatus without actually departing from the true spirit and scope of this invention.

I claim:

1. A gas burner having a hollow body adapted to have a combustible gas and air mixture admitted at the upstream end thereof and flow therethrough to issue at the downstream end thereof, comprising:

a head portion having spaced walls defining a port from which the gas and air mixture issues for combustion adjacent said port;

said spaced walls having a first pair of spaced edges defining a region of said port having an enlarged width and a second pair of spaced edges defining a region of said port having a reduced width; and

a crossover portion entirely upstream of said head portion and adjacent said region of reduced width whereby ignition of the gas and air mixture issuing from said port may be effected from a flame present at said crossover portion.

2. The invention of claim 1 wherein said head portion and said crossover portion are integrally formed from cast iron.

3. The invention of claim 2 wherein said crossover portion comprises a boss projecting laterally from the body of said burner, said boss having at least one elongated slot therein adjacent said region of reduced width.

4. The invention of claim 1 wherein said edges defining said port are inclined upwardly and rearwardly toward the upstream end of said body whereby said port is also inclined

5

with its upper extremity terminating adjacent said crossover portion.

5. A gas burner having a hollow cast iron body adapted to have a combustible gas and air mixture admitted at the upstream end thereof and flow therethrough to issue at the downstream end thereof comprising:

a venturi portion having an upstream end into which the gas and air mixture is introduced;

a crossover portion downstream of said venturi portion;

a head portion downstream of said crossover portion and having spaced walls defining a port from which the gas and air mixture issues for combustion adjacent said port; said spaced walls having a first pair of spaced edges defining a region of said port having an enlarged width and a second pair of spaced edges defining a region of said port having a reduced width;

said crossover portion comprising a boss projecting laterally from the body of said burner, said boss having at least one elongated slot therein adjacent said region of reduced width; and

said edges defining said port being inclined upwardly and rearwardly toward the upstream end of said body whereby said port is also inclined with its upper extremity terminating adjacent said crossover portion.
